CLOTHES-PRESSING MACHINE.

1,141,901.

Specification of Letters Patent. Patented June 1, 1915.

Application filed July 5, 1910. Serial No. 570,886.

To all whom it may concern:

Be it known that I, THEODORE D. PALMER, of Syracuse, in the county of Onondaga, in the State of New York, have invented new and useful Improvements in Clothes-Pressing Machines, of which the following, taken in connection with the accompanying drawings, is a full, clear, and exact description.

This invention relates to certain improvements in the method of and apparatus for pressing clothes whereby garments, such as coats, vests, trousers, skirts and similar wearing apparel may be subjected to direct mechanical pressure and also to air pressure of two or more atmospheres through one or both of the pressing elements simultaneously with the mechanical pressure.

The main object is to enable such garments to be dry-pressed with or without the use of moisture, so as to materially increase the output of the machine for a given period of time without liability of injuring the fabric. In other words, I have sought to render the pressing operation more expeditious by the use of air or similar comparatively dry fluid introduced under pressure through one or both of the pressing elements, while the latter are in their pressing positions, and to provide mechanical means for holding said pressing elements in their pressing position with a greater degree of pressure than that of the fluid tending to force these elements apart.

Another object is to provide means for heating the pressing fluid under pressure after entering one or both of the pressing elements.

A still further object is to provide means under the control of the operator, whereby the flow of the pressure fluid, as air, may be utilized to draw a suitable amount of moisture therewith into one or both of the pressing elements.

Other objects and uses will be brought out in the following description.

In the drawings: Figure 1 is a top plan of a clothes pressing machine embodying the various features of my invention, the ends of the table being broken away. Fig. 2 is an end elevation partly broken away and partly in section of the machine shown in Fig. 1. Fig. 3 is a detail sectional view of the coupling between the air and moisture supply pipes. Fig. 4 is a detail view showing the manner of connecting the pedal lever to the

frame and with the upwardly projecting pawl 22.

This machine comprises two pressing elements —1— and —2— disposed one above the other, the lower pressing element —1— upon which the clothes or garments to be pressed are placed, being mounted upon a suitable supporting bracket —3— some distance above a horizontal table —4—, said bracket and table being secured to a main supporting frame —5—. The lower pressing element —1—, which will hereafter be termed the "buck," is provided with a steam chamber —6— having a laminated foraminous top composed of a perforated metal plate —7— and a suitable fabric covering or press cloth —8—, the latter being secured to the periphery of the buck —1— by clamping members —9—. The chamber —6— of the buck —1— is provided with an inlet —10— preferably in the bottom thereof and, between this inlet and the perforated plate —7—, and within the chamber —6—, is located a hollow baffle-plate —11— having an inner heating-chamber —12— opening at the ends to the atmosphere for ventilation. Arranged lengthwise within the heating-chamber —12— is a gas burner —13— having an inlet-pipe —14— adapted to be connected to any available source of supply, not shown. The function of the burner —13— is to heat the walls of the hollow baffle-plate —11—, so as to more effectively superheat the fluid under pressure which is introduced through the inlet —10—, the latter being connected in a manner hereinafter described to a compressed-air reservoir —15— and moisture as water supply reservoir —16—, shown in Figs. 1 and 2.

The superposed press-head —2— is secured to the front end of a vertically movable swinging-frame or lever —17— which is fulcrumed intermediate its ends upon suitable brackets —18— forming a part of the main supporting frame —5—, the rear end 100 of the lever being provided with weights —19— adjustable thereon, slightly overbalancing the weight of the head —2— and normally rocking it to its up-position when the machine is not in use. The press-head —2— 105 may be forced to and held in its pressing position by the pressure of the foot upon a pedal lever —21— which is fulcrumed upon the main supporting frame —5— and is provided at its rear end with an upwardly pro-

jecting pawl —22— having a shoulder —23— movable into and out of engagement with an abutment —24— on the rear end of the rocking-frame or lever —17—. When it is desired to raise the head —2— after the pressing operation, the pawl —22— may be thrown from its holding position by means of a tripping device —25— having an operating member —26— extending across the top of the machine and terminating at its front end in a handle —27—, the tripping device —25— being pivoted to the rear end of the lever —17—. The press head —2—, like the buck —1—, is hollow and its inner chamber, as —28—, is provided with a laminated foraminous bottom consisting of a perforated press plate —29— and a fabric covering —30— extending across the bottom of the perforated plate —29— and secured to the marginal edges of the head —2— by clamping members —31—. The chamber —28— is provided, preferably in its upper side or top, with an inlet —32— which is also connected, in a manner herein-after described, to the air pressure tank —15— and moisture supply tank —16—. A hollow baffle plate —33—, similar to the baffle plate —11— in the buck —1—, is located within the chamber —28— directly between the inlet —32— and perforated press plate —29—, and is provided with a heating chamber —34— in which is located a gas burner —35— having a supply pipe —36— adapted to be connected to the same source of supply as the pipe —14—. The chamber —34— is also open at both ends to the atmosphere, as more clearly shown in Fig. 1. The object in providing the baffle plate —33— with a heating chamber, is to more effectively superheat or increase the temperature of the compressed air or moisture laden air after it has entered the head and just before passing through the perforations onto the garment.

The fuel supply pipes —14— and —36— may be provided with suitable valves whereby either may be used independently of the other, or both burners may be cut off or used simultaneously, as may be desired.

The connections between the reservoirs —15— and —16— and interiors of the buck —1— and head —2—, are such that the supply of compressed air or moisture may be entirely cut off and the clothes pressed by mechanical pressure alone; or air pressure may be supplied to either of the pressing elements independently of the other, or to both elements simultaneously, or the flow of the compressed air from the reservoir —15— to either or both of the pressing elements may be utilized to draw more or less moisture from the moisture supply reservoir —16— into said pressing element or elements simultaneously with the air pressure. For this purpose I have shown the

reservoirs —15— and —16— as provided with out-flow pipes —38— and —39— connected to each other and to a single supply pipe —40— by a coupling —41—. This coupling is provided with two branch passages —42— and —43— converging upwardly and communicating at their points of convergence with the supply pipe —40—, the branch passage —43— being preferably restricted in size so that when compressed air is flowing through the pipe —38—, it will draw a limited amount of moisture from the reservoir —16— through the restricted passage —43— and convey the same into the pipe —40—. This pipe —40— is connected to a suitable gland or stuffing box —44— coaxial with the axis of movement of the head supporting lever —17—, and in this gland is journaled one end of a supply pipe —45— leading to the inlet —32— of the head —2—, the portion of the supply pipe —45— adjacent the head —2— being provided with a normally closed valve —46— having a suitable hand-lever —47— adapted to be opened at will by the operator to supply compressed air to the perforated press head —2— during the pressing operation. The portion of the supply pipe —45— between the valve —46— and gland —44— is connected by a branch pipe —48— to an opposite gland —49— also coaxial with the axis of movement of the lever —17—, and is provided with a normally closed valve —50— having an operating member —51— by which it may be opened at will. The gland —49— is connected by a pipe —52— to the inlet —10— of the buck —1—, so that when the valve —50— is opened compressed air will also be admitted to the chamber —6— of said buck. It is now clear that when both valves —46— and —50— are opened compressed air will be simultaneously introduced into the pressing elements through their perforated presser plates and against opposite surfaces of the garment, thereby pressing the garment simultaneously by air and mechanical pressure when the pressing elements are brought together.

The up-flow pipe —39— leading from the moisture supply tank —16— is provided with a valve —54— which may be opened to varying degrees to allow the up-flowing compressed air to draw a limited amount of moisture in the form of a spray therewith into either or both of the pressing elements, as may be desired, by simply opening the valve —46— or valve —50— or both of said valves simultaneously, thereby supplying a limited quantity of moisture to the garment when necessary, as for example in pressing heavy or thick fabrics.

It is now apparent that the garment may be pressed under cushion pressure from one or both sides by atmospheric air by simply

bringing the pressing elements together with sufficient pressure to reasonably confine the air within the area of the pressing plates, although additional mechanical pressure 5 may be applied if necessary by simply depressing the pedal —21—. It is also clear that this atmospheric air or moisture laden air may be heated in either of the pressing elements independently, or in both of them 10 simultaneously, after entering such elements by means of the burners —13— and —35—.

An important feature of advantage of this construction is that I avoid the use of an extra steam boiler which usually accompanies 15 the steam clothes pressing machines, and it is for this purpose that I have introduced the hollow baffle plates —11— and —33— and provided them with inner burners, so that when an extra amount of moisture is desired it may be converted into 20 steam within either or both of the pressing elements. Each hollow deflector including its heating chamber and burner constitutes a steam generator located wholly within the 25 corresponding pressing element. The sides of the heating chambers are spaced apart from the adjacent portions of the pressing elements to allow the steam to pass from the inlet entirely around the heating chambers, 30 and thence through the perforated press plates, thereby affording a large heating area directly in the path of the inflowing moisture laden air to quickly convert the moisture into steam, if desired.

Atmospheric air may be maintained under compression in the reservoir —15— by any suitable device, not necessary to herein illustrate or describe.

When it is desired to press a garment by 40 atmospheric air under pressure, the valve —34— in the up-flow pipe from the moisture supply tank —16— will be closed and the garment may be spread out upon the upper surface of the buck —1—, whereupon 45 the head —2— may be depressed by means of a handle —60— until engaged with the garment, in which position it will be automatically locked by the engagement of the pawl —22— with the abutment —24—. 50 Either or both of the valves —46— or —50— may then be opened to admit the atmospheric air under pressure to either or both of the pressing elements, and through their pressing plates directly against one or both 55 faces of the garment, thereby effectively pressing such garment mainly under air pressure, although if desired the upper press head may be brought down with greater pressure upon the garment by means of the 60 pedal —21—.

If in pressing heavy or wrinkled garments it is desired to apply moisture to such garment, the valve —54— may be opened by hand or by means of an operating rod 65 —61— and handle —62—, as shown in Fig.

2, so that when one or both of the valves —46— or —50— is or are opened, the inflowing air under pressure into the pressing elements will automatically draw limited quantities of moisture in spray form 70 from the reservoir —16— into said elements and through their presser plates against the garment, it being understood that during either one of these operations the inflowing fluid may be heated or converted into steam by coming into contact with the sides of the heating chambers —11— or —33—.

What I claim is:

1. In a clothes pressing machine, two pressing elements one of which is provided with a foraminous presser plate and an internal heater in combination with means for introducing compressed air into the pressing element having the perforated press- 80 plate and heater whereby the air is heated in transit through the perforations.

2. In a clothes pressing machine, two pressing elements one of which is movable toward and from the other, one of said elements 90 having a foraminous press-plate, and means for mixing air under pressure and moisture and supplying the mixture to the interior of the pressing element having the perforated press-plate.

3. In a clothes pressing machine, two pressing elements one of which is movable toward and from the other, one of said elements having a foraminous press-plate, and means for supplying water spray under pressure 100 to the interior of the pressing element having the foraminous press-plate.

4. In a clothes pressing machine, two pressing elements one of which is movable toward and from the other one of said elements 105 having a foraminous press-plate, means for supplying moisture in the form of a spray to the interior of the pressing element having the foraminous press-plate, and means within the pressing element having the 110 foraminous press-plate for converting such moisture into steam.

5. In a clothes pressing machine, a source of supply for compressed air, two hollow pressing elements connected to said source 115 of supply and provided with foraminous press-plates, and separate devices for controlling the flow of compressed air to said elements whereby compressed air may be supplied to either face of the garment independently of the other or to both faces simultaneously.

6. In a clothes pressing machine, two hollow pressing elements having perforated press-plates and fabric coverings for said 125 plates, and means for introducing moisture laden air into said elements independently of each other or simultaneously.

7. In a clothes pressing machine, two hollow pressing elements having perforated 130

press-plates and fabric coverings for said plates, means for introducing moisture laden air into said elements independently of each other or simultaneously, and heaters located 5 within said elements for converting the moisture of the air into steam.

8. In a clothes pressing machine, two pressing elements, one of which is provided with a perforated press plate and a press cloth 10 covering said plate; separate reservoirs containing different fluids; means for conducting said fluids to a single pipe leading to the interior of the pressing element having a perforated press plate; with means for controlling the flow of the mixture from said 15 single pipe; and means for bringing said pressing elements together.

9. In a clothes pressing machine, two co-acting pressing elements, one of which is 20 hollow and provided with a perforated press plate and a press cloth covering said plate; separate reservoirs, one adapted to contain air, the other water; pipes leading from said reservoirs and merging into a single pipe 25 which leads to the interior of a hollow pressing element; a means for regulating the flow from said single pipe; the fluid in one of the reservoirs being under pressure; and means for bringing said pressing elements 30 together.

10. In a clothes pressing machine, two pressing elements, one of which is hollow and provided with a foraminous press plate, separate reservoirs containing different 35 fluids, pipes leading from said reservoirs and merging into a single pipe which is

connected to the interior of the hollow pressing element, the fluid in one of the reservoirs being under pressure and a valve in the pipe leading from the other reservoir and a separate valve in a single pipe for controlling the flow of the fluid to the interior of the hollow pressing element. 40

11. In a clothes pressing machine, two hollow pressing elements having foraminous 45 press plates, hollow baffle plates within the pressing elements, burners within the baffle plates for heating the same, separate reservoirs containing different fluids, the fluid in one reservoir being under pressure, the pipes 50 leading from said reservoirs and merging into a single pipe, said single pipe having branch pipes discharging into the pressing elements and against the baffle plates therein and separate valves in the branch pipes. 55

12. A clothes pressing machine comprising a hollow press head, having a perforated face plate; a buck; means for causing said press head to come in contact with a garment placed on the buck; means for 60 supplying said head with air and moisture; and means for heating said air and moisture and forcibly discharging the same through said perforated face plate onto a garment placed on the buck. 65

In witness whereof I have hereunto set my hand on this 1st day of July 1910.

THEODORE D. PALMER.
